(57) **CLAIM**

The ornamental design for a carton, as shown and described.

DESCRIPTION

FIG. 1 is a perspective view of the carton embodying my new design;

FIG. 2 is a top planar view, the bottom view being a mirror image thereof;

FIG. 3 is a left side elevational view, the right side elevational view being a mirror image thereof;

FIG. 4 is a front elevational view thereof; and,

FIG. 5 is a rear elevational view.

The broken lines in the drawings represent unclaimed environmental subject matter.
